UNITED STATES PATENT OFFICE.

JANG LANDSING, OF BOONTON, NEW JERSEY, ASSIGNOR, BY MESNE ASSIGNMENTS, TO GENERAL STORAGE BATTERY COMPANY, OF NEW YORK, N. Y., A CORPORATION OF NEW YORK.

STORAGE BATTERY.

No. 839,606.

Specification of Letters Patent.

Patented Dec. 25, 1906.

Application filed November 24, 1905. Serial No. 288,848.

To all whom it may concern:

Be it known that I, JANG LANDSING, a citizen of the United States, and a resident of Boonton, Morris county, State of New Jersey, have invented certain new and useful Improvements in Storage - Battery Plates, of which the following is a specification, accompanied by drawings.

This invention relates to improvements in storage-battery plates, more particularly to Planté plates, in which the active material is formed out of and upon lead portions of the electrodes by chemical or electrochemical action.

15 The object of the present invention is to improve upon the construction of such Planté plates and prevent the plate from buckling as the lead strips thicken and elongate in the process of formation.

20 Further objects of the invention will hereinafter appear; and to these ends the invention consists of a storage-battery plate for carrying out the above objects embodying the features of construction, combinations of 25 elements, and arrangement of parts having the general mode of operation substantially as hereinafter fully described and claimed in this specification and shown in the accompanying drawings, in which—

30 Figure 1 is a side view of a portion of a plate embodying the invention. Fig. 2 is a side view of a portion of a plate embodying a modification. Figs. 3 and 4 are side views of portions of modified plates, and Figs. 5 and 35 6 are side views of portions of modified plates.

Referring to the drawings, A and B represent the sides or framework of the plate, which may be of lead or an alloy, as lead and 40 antimony.

C represents a vertical cross-rib, and D is a horizontal cross-rib.

Within the space formed by the frame A B and cross-ribs C D is shown a panel or elementary grill of lead constructed in accordance with this invention in such manner as to prevent buckling. The complete plate may be made up of as many elementary panels or grills forming unit elements as desired, but one grill being shown by way of illustration.

As shown, the grill comprises the elementary units or strips E, adapted to become

active, and these strips or units are connected by flexible cross members or supports F. As shown, short ends G of the unit elements project beyond the upper and lower cross-supports F, and spaces H are provided between said ends and the frame and ribs to permit elongation of the grill longitudinally or in the direction of the extent of the unit strips E. Spaces I are formed at each side of the grill substantially opposite the ends of the cross members or supports F to permit sidewise elongation of said members. According to the construction shown and described in Fig. 1 provision is afforded for both elongation and thickening of the unit strips E and of the cross members or supports F.

70 In Fig. 2 a construction substantially like Fig. 1 is shown, with the addition of a central space J in the grill, so that the grill may expand inward from either side to fill the space, thus preventing the outer portions of the grill from pressing outward and bulging against the outside frame of the plate, which might also be distorted by such action.

In Fig. 3 continuous side spaces K are provided at each side of the grill to permit transverse expansion of the grill, and the extreme cross members or supports F are connected to the frame and cross-ribs by means of flexible bent straps L, which permit the grill to expand both longitudinally and transversely, or, in other words, in all directions.

85 In Fig. 4 a modification of Fig. 3 is shown, in which the spaces K are provided at each side of the grill; but the connecting-strips L' extend from the grill to the frame and ribs toward each other instead of away from each other, while additional spaces O are provided between said strips L' and the frame and cross-ribs, so that additional provision for expansion is made and the grill may expand in all directions into the recesses H, O, and K.

90 In Fig. 5 a modification is shown in which the grill is connected at the corners by diagonal strips P, extending across the corners and leaving spaces Q in the corners. The spaces H are provided, as before, at the ends of the grill, and the spaces K are provided at the sides. According to this construction the grill may expand in all directions and the corner-spaces receive the expansion from two directions.

In Fig. 6 the cross supports or members which connect the unit strips are crooked or broken, and spaces are left between the broken ends, into which they may expand 5 within the grill. The broken pieces of the cross supports or members are represented by R, and the spaces to permit expansion are represented by S. As before, spaces H are provided at the ends of the grill to provide 10 for expansion.

The plate may be formed in any desired manner, one satisfactory method being to cast the individual grills in any desired manner and then assemble as many as necessary 15 for the plate and cast the frame around them.

I claim, and desire to obtain by Letters Patent, the following:

1. A Planté battery-plate having a frame provided with ribs, active members in the 20 form of unit strips supported at a plurality of points by cross-supports secured to the ribs, said plate having intervals opposite the ends of the strips to afford provision for expansion, the outer cross-supports being connected by 25 flexible strips to the corners of the frame, the plate also having spaces opposite the ends of the cross-supports to permit expansion.

2. A Planté battery-plate having a frame provided with ribs, active members in the 30 form of unit strips supported at a plurality of

points by cross-supports secured to the ribs, said plate having intervals opposite the ends of the strips to afford provision for expansion, the outer cross-supports being connected by 35 flexible strips to the corners of the frame and to the ribs, the plate also having spaces opposite the ends of the cross-supports to permit expansion.

3. A Planté battery-plate provided with active portions, having one or more grills embodying strips and cross-supports, said grills being held and surrounded by the battery-plate, ribs or supports in a manner leaving intervals at the ends of the strips for permitting the elongation of the strips, the cross-supports being of sufficiently yielding design to accommodate the elongating movement, the grills being connected to the corners of the frame and to the ribs by short flexible members, and the plate also being provided with 45 intervals opposite the ends of the cross-supports.

In testimony whereof I have signed this specification in the presence of two subscribing witnesses.

JANG LANDSING.
